(57) **CLAIM**

I claim the ornamental design for a tee box marker advertising device, as shown and described.

DESCRIPTION

FIG. 1 is a top perspective view of a tee box marker advertising device, showing my new design;

FIG. 2 is a left-side elevational view thereof, the right-side elevational view being a mirror image thereof;

FIG. 3 is a front elevational view thereof, the rear elevational view being a mirror image thereof;

FIG. 4 is a top plan view thereof;

FIG. 5 is a bottom plan view thereof; and,

FIG. 6 is a bottom perspective view thereof.

The broken lines showing text and an advertisement in FIG. 1 depict environmental matter and form no part of the claimed design.
